UNITED STATES PATENT OFFICE.

JAMES H. WATT, OF BARNESVILLE, OHIO.

COMBINED FLUE-BASE AND THIMBLE.

SPECIFICATION forming part of Letters Patent No. 496,626, dated May 2, 1893.

Application filed December 10, 1892. Serial No. 454,707. (No model.)

To all whom it may concern:

Be it known that I, JAMES H. WATT, of Barnesville, in the county of Belmont and State of Ohio, have invented certain new and useful 5 Improvements in a Combined Flue-Base and Thimble; and I do hereby declare that the following is a full, clear, and exact description thereof, reference being had to the accompanying drawings, and to the letters of reference 10 marked thereon, which form part of this specification.

This invention is designed for use in houses where flues are built up from upper stories only, instead of from the ground, and its object 15 is to provide a combined pipe thimble and flue-base, and it consists in the novel construction and combination of parts hereinabove described and claimed.

In the drawings:—Figure 1 represents a side 20 view of the thimble in position, with flue superimposed thereon. Fig. 2 is an enlarged vertical transverse section through the thimble. Fig. 3 is a top view; Fig. 4 a transverse horizontal sectional view thereof looking 25 downward.

A designates the top plate, preferably rectangular, and of such size that the brick flue Z may be built thereupon. It has a central opening around which is a depending collar 30 A' of sufficient length to extend through the floor and ceiling of an ordinary building.

B designates the bottom plate, having a central opening to receive the lower end of collar A', and preferably circular. It is attached to 35 plate A by means of bolts C, C, the lower ends of which may be formed with eyes c, engaging hooks b, b, secured to the upper side of plate B. On the upper surface of plate B are formed equidistant radial lugs D, D, which 40 may be transversely notched as at d, d.

E is a cylinder of larger diameter than collar A', and surrounding the same, being confined between plates A, B, and supported on the latter. The lower edge of this cylinder 45 rests in notches d of lugs D, by which it is centered around the collar. The cylinder has two or more series of equi-distant notches e and e' in its lower edge; notches e' being deeper than notches e; there are as many 50 notches e, e', as there are lugs D. By revolving said cylinder its notches e, or e' can be engaged with lugs D, and thus be lowered

more or less toward plate B. When the plain edge of cylinder rests on the lugs it is upheld entirely off plate B, when notches e are set 55 over lugs it is slightly lowered, and when notches e' are set over the lugs its plain edge will rest on the surface of the plate B. By this means provision is made for adjusting the thimble to floors and ceilings of different 60 thicknesses, and at the same time provision is made for an air circulation around the collar, and between it and the cylinder. Fresh air may be admitted into the space between the collar and cylinder through holes b' in 65 plate B, as shown.

In applying a thimble a hole is cut through the floor and ceiling at the desired place and the plate A laid thereover, collar A' depending through the opening, the plate A resting 70 on the girders or sleepers of the flooring. The cylinder is then slipped around the collar, and plate B slipped thereon, and bolted to plate A, as indicated in the drawings the lower surface of plate B being flush with the plastering on the ceiling. A durable, safe and well fitting thimble is thus made, and the stove pipe can be run into the flue through the collar without danger. The device may also be 75 employed as a register for hot air. 80

The collar and top plate may be cast in one piece; the device gives additional security against accidental fires, as the pipe and collar are both kept out of contact with the joints or ceiling, and a free circulation of air is admitted between the cylinder and collar, and a neater finish can be made by plastering up to the lower plate, than can be made in ordinary arrangements where the box extends from the floor through the joist and to the 90 lower edge of the ceiling. 85

Having thus described my invention, what I claim as new, and desire to secure by Letters Patent thereon, is—

1. The combination of the top plate, the collar, the bottom plate having lugs on its upper surface and means for uniting said plates; with the cylinder, having notches on its lower edge, supported on the lugs, confined between the plates, and inclosing the collar, substantially as specified. 95

2. The combination of the top plate having a central opening and a depending collar around said opening, the bottom plate having 100

lugs on its upper surface, the bolts connecting the top and bottom plates, the cylinder surrounding the collar mounted on the lugs of the bottom plate and confined between said 5 plates, the bottom plate having perforation to admit passage of air between the cylinder and collar, all constructed and arranged substantially as and for the purpose set forth.

In testimony that I claim the foregoing as my own I affix my signature in presence of two witnesses.

JAMES H. WATT.
